Patent expires May 17, 1964

3 Claims. (Cl. 259—161)

1

The present invention relates to apparatus for the malaxing of various materials.

Existing apparatus of this kind, and in particular concrete mixers, which include a rotary drum and means for loading this drum, for instance through an elevator bucket, work on the following cycle of operation:

Loading of the drum, malaxing of the materials present therein, emptying of this drum and return thereof into loading position.

Now, in this sequence of operations, only the malaxing one corresponds to productive work, and the time absorbed by the other operations is a lost time.

The object of the present invention is to provide an apparatus of the type above referred to which avoids this drawback, that is to say with which the whole of the time of operation is truly spent in the malaxing of materials.

With this object in view, according to a feature of my invention, the apparatus includes three drums movable in such manner as to be able successively to come into filling, malaxing and emptying positions, and means for rotating these drums about their respective axes at least during the period for which they are in malaxing position.

According to a preferred embodiment of my invention, the respective axes of the drums are located in the same plane and meet in a common point, and in order to cause them to pass successively through their filling, malaxing and emptying positions means are provided for rotating the whole of said drums about an axis, practically horizontal, passing through this common point and perpendicular to the plane of the respective axes of the drums.

Owing to this particular arrangement, the rotation of each drum about its axis can be combined with the pivoting of the whole about the common horizontal axis through a mechanism analogous to that of the satellite pinions of differential gears.

On the other hand, the movement of rotation of the whole of the drums about a horizontal axis causes each of the drums successively to come, for the emptying thereof, into a substantially vertical position where it is upside down, and the fact of emptying the drums in this way constitutes a serious advantage.

A preferred embodiment of my invention will be hereinafter described, with reference to the accompanying drawings, given merely by way of example, and in which:

Fig. 1 is a diagrammatic lateral view of a

2

concrete mixer made according to my invention.

Figs. 2 and 3 are partial views showing the various positions of the drums in the course of a revolution.

Fig. 4 is a diagrammatical view of the mechanism for controlling the winch, the drum unit locking means, and the device for emptying into each drum the amount of water necessary for the malaxing.

10 Drums 1, 2 and 3 are mounted on respective axes 4, 5, 6, themselves fixed on the common main shaft 7, journalled in bearings 8 of frame 9. Each drum includes a bevel toothed ring 10, 11, 12, in mesh with a common bevel toothed wheel 13. The latter is driven by a motor 14 through a chain 15.

The loading device includes a bucket 20 pivoted at 20a to frame 9 and driven by a cable 18, wound on a winch 17 operated by a motor 14 through a chain 16. Fig. 1 shows, in solid lines, bucket 20 in the upper position for the loading of drum 1, and, in dotted lines, in the lower position, in which the material contained in wagon 23 can be poured into said bucket.

25 At the upper part of the frame is provided a water tank 22 which permits, through a feed tube 22a, of pouring the desired amount of water into the drum (1 on the drawing) that is in loading position. Finally, a wagon 24, adapted to pass under the frame of the concrete mixer, can be brought into position for receiving the malaxed mixture which flows from the drum (2 in the drawing) which is in the emptying position.

The axle of the wheels 25 of the concrete mixer is adapted to receive steering displacements in order to permit of driving the mixer on a road when it rests upon its wheels 25—26.

In the working position, wheels 25—26 are mounted on supports of suitable height to enable wagon 24 to circulate under the concrete mixer frame.

Winch 17 is controlled through a lever 21.

As shown by Fig. 1, winch 17 is driven by a motor 14 through a chain 15 meshing with a toothed wheel concentric with shaft 7 and a chain 16 meshing with another toothed wheel rigid with the first. Chain 16 cooperates with a bevel toothed wheel 30 (Fig. 4) in mesh with two opposed bevel pinions 31 and 32 mounted 30 loose on the shaft 33 of winch 17. Control lever 21 is adapted to operate a sleeve 34 slidably keyed on shaft 33. This sleeve 34 and pinions 31 and 32 carry corresponding teeth or projections which permit of coupling 34 with one or the other of pinions 31 and 32. By pivoting lever 21 toward

the left, pinion 32 is coupled with sleeve 34 and shaft 33 is rotated in the direction of arrow *f*, thus winding cable 18 on winch 17. On the contrary, if lever 21 is pivoted in the opposite direction, sleeve 34, and therefore shaft 33, are coupled with pinion 31, driven by motor 14 in the direction opposed to that of pinion 32.

Shaft 33 includes a threaded portion 35 on which is engaged a carriage 36 held in such manner as to be prevented from turning with the shaft but to be able to slide parallelly thereto. This carriage is provided with a fork 37 arranged to cooperate with a bent lever 38 connected to a rod 39. On this rod 39 are mounted two levers 40 and 41 which control cocks 42 and 43 respectively. These cocks are mounted on their control levers in such manner that when one of them is opened, the other is closed, and vice versa. The carriage is further provided with a finger 44 adapted to cooperate with a lever 46 connected through rods 47 and 48 and bell crank levers 49 and 50 with a sliding rod 51 pushed by a spring 52 toward a cam 53 provided with notches 53a which is fixed on shaft 7.

The working of this device is as follows:

In the position shown by Fig. 4, tank 22 has been nearly filled through pipe 22b. Lever 21 is inclined in the leftward direction, sleeve 34 is in mesh with pinion 32, shaft 33 is rotating in the direction of arrow *f* and carriage 36 is moving toward the left. On the other hand, at this time, the shaft 7 has been released due to rod 51 being pulled out, through system 44, 45, 46, 47, 48, 49, 50, from the notch 53a of cam 53 in which it was engaged. Finally winch 17 is turning in the direction of winding of cable 18 and bucket 20 is moving upwardly and getting near to its upper extreme position.

After a short time, lever 45 escapes from engagement with finger 44 and consequently releases lever 46 and also transmission 47, 48, 49 and 50; rod 51 is therefore brought back by its spring 52 toward cam 53. But as this cam has already turned from the position shown by Fig. 4, the end of rod 51, instead of reentering the notch 53a from which it has been pulled, comes to bear against the circular periphery of the cam.

Shaft 7 is therefore free to keep rotating until it is automatically stopped by the next notch 53a coming opposite rod 51. In the course of this rotary movement, which corresponds to an angle of 120°, the three drums change of position, that is to say the one that was in filling position comes into malaxing position, the one that was in malaxing position comes into emptying position, and finally the one that was in emptying position comes into filling position. This permutation will take place relatively quickly because, as soon as the unit formed by the whole of the three drums is released, the resistance opposed by each drum to its movement of rotation about its own axis tends, by reaction, to facilitate the rotation of this unit carried by shafts 7, which, on the other hand, has a tendency to be driven by friction by wheel 13. Furthermore, as soon as the drum that was in filling position has moved past the vertical, the whole becomes unbalanced so that the rotation is accordingly accelerated. Consequently, in a very short time the three drums come to occupy their new positions.

Immediately after this, the branch 37a of the fork carried by carriage 36 moves lever 38 and produces, through rod 39 and levers 40 and 41, the closing of cock 42 and the opening of cock 43. The water present in tank 22 therefore flows

through conduit 22a into the drum that is in filling position.

Winch 17 finishes its winding movement and bucket 20 empties the materials it contains into said drum in filling position.

Sleeve 34 is then disengaged from pinion 32 as lever 21 is pivoted in the opposed direction by the operator (or by an automatic disengagement device).

As sleeve 34 is now in engagement with bevel pinion 31, shaft 33 starts rotating in a direction opposed to that of arrow *f* and carriage 36 starts back toward the right. In the course of this sliding movement finger 44 comes back at a given time to place itself on the right hand side of lever 45 so as to be again ready to work for the next release of shaft 7.

Also in the course of this movement from left to right of carriage 36, the arm 37b of the fork formed on carriage 36 comes, at a given time, to push toward the right the end of the lower branch of bent lever 38 and thus causes the closing of cock 43 and the opening of cock 42. Tank 22 which had emptied through 22a starts replenishing through 22b.

Likewise, during this time, bucket 20 has moved back downwardly, since now winch 17 turns in the cable unwinding direction. It reaches its lower position, shown in dotted lines, when carriage 36 reaches the end of its displacement toward the right.

At this time, sleeve 34 is disengaged from pinion 31, as a result of lever 21 being brought back into vertical position by the operator (or by an automatic disengagement device).

Bucket 20 is filled by the tipping of wagon 23. Then the operator displaces lever 21 toward the left, in such manner as to engage sleeve 34 with pinion 32. The shaft is then driven in the direction of the arrow, and carriage 36 moves toward the left.

Winch 17 is being wound, and the loaded bucket 20 is moved upwardly.

Finger 44 comes to bear on lever 45 and, through transmission 46-47-48-49-50, pulls bolt piece 51 from the notch 53a it occupies.

The parts come back to the position shown by Fig. 4 and the operation is repeated.

While I have, in the above description, disclosed what I deem to be a practical and efficient embodiment of the present invention, it should be well understood that I do not wish to be limited thereto as there might be changes made in the arrangement, disposition and form of the parts without departing from the principle of the present invention as comprehended within the scope of the appended claims.

What I claim is:

1. A concrete mixer which comprises, in combination, a frame, a horizontal shaft journalled in said frame, at least three pivot axes carried by said shaft located in a plane at right angles thereto, rotary drums carried by said axes, respectively, a motor, transmission means, including a driving wheel journalled on said shaft and at least three satellite pinions each rigid with one of said drums, respectively, and operatively connected with said wheel, for transmitting the motion of said motor to said drums, a water tank carried by said frame, means for filling and emptying said tank, an elevator bucket movably mounted in said frame so as to have, in its upper position, its outlet close to that of said tank, a winch for operating said bucket, means for locking said shaft in any of at least three given

positions for each of which one of said drums is under said tank and bucket outlets, control means for intermittently bringing said locking means out of action to allow said shaft to pass from one position to the next one, and means interrelated with said control means for operating said tank filling and emptying means and said winch in synchronism with the movements of said shaft.

2. A concrete mixer which comprises, in combination, a frame, a horizontal shaft journalled in said frame, at least three pivot axes carried by said shaft located in a plane at right angles thereto, rotary drums carried by said axes, respectively, a motor, a driving bevel wheel journalled on said shaft operatively connected with said motor, at least three satellite pinions each rigid with one of said drums, respectively, and in mesh with said wheel, for transmitting the motion of said motor to said drums, a water tank carried by said frame, means for filling and emptying said tank, an elevator bucket movably mounted in said frame so as to have, in its upper position, its outlet close to that of said tank, a winch for operating said bucket, means for locking said shaft in any of at least three given positions for each of which one of said drums is under said tank and bucket outlets, control means for intermittently bringing said locking means out of action to allow said shaft to pass from one position to the next one, and means interrelated with said control means for operating said tank filling and emptying means and said winch in synchronism with the movements of said shaft.

3. A concrete mixer which comprises, in combination, a frame, a horizontal shaft journalled in said frame, three pivot axes carried by said shaft located in a plane at right angles thereto,

rotary drums carried by said axes, respectively, a motor, a driving bevel wheel journalled on said shaft operatively connected with said motor, at least three satellite bevel pinions each rigid with one of said drums, respectively, and in mesh with said wheel, for transmitting the motion of said motor to said drums, a water tank carried by said frame, means for filling and emptying said tank, an elevator bucket movably mounted in said frame so as to have, in its upper position, its outlet close to that of said tank, a winch for operating said bucket, means for locking said shaft in any of at least three given positions for each of which one of said drums is under said tank and bucket outlets and another one is upside down, with its axis vertical, control means for intermittently bringing said locking means out of action to allow said shaft to pass from one position to the next one, and means interrelated with said control means for operating said tank filling and emptying means and said winch in synchronism with the movements of said shaft.
